(57) **CLAIM**

The ornamental design for a front face of a wheel, as shown and described.

DESCRIPTION

FIG. 1 is an front elevational view of a front face of a wheel showing our new design; and,

FIG. 2 is a perspective view thereof.

The broken line showings of the hub, and the lug nut areas are for illustrative purposes only and form no part of the claimed design.

1 Claim, 1 Drawing Sheet

FIG. 1

FIG. 2
